WILLIAM C. UHRI, JR., OF ST. LOUIS, MISSOURI, ASSIGNOR, BY MESNE ASSIGNMENTS, TO
CENTRAL ENGINEERING & SALES COMPANY, OF ST. LOUIS, MISSOURI, A CORPORA-
TION OF MISSOURI

APPARATUS FOR PRODUCING A STREAM OF ATOMIZED LIQUID

Application filed May 2, 1928. Serial No. 274,548.

My invention relates to the art of washing and drying by means of fluid discharge through a nozzle and my invention consists in a novel nozzle adapted to be used for such 5 purpose.

My nozzle has been designed particularly for use in the washing, drying, and vacuum cleaning of motors, the exteriors and interiors of motor vehicles, machinery and 10 other objects of various descriptions in which difficulties are encountered due to accumulations of dirt, mud, oil, and grease; also for the purpose of removing substances capable of being dissolved in fluids. However, I believe 15 that my nozzle is adapted for a much wider field of use than that outlined above and I contemplate its application to various uses.

It has been customary heretofore to apply 20 water under pressure and efforts have been made to increase the pressure on the water by the use of compressed air supplied to the water discharge device in such a way as to render the water stream more effective.

One object of my invention is to provide a 25 discharge nozzle which will operate more effectively than similar devices previously used and will so operate with a source of water supply under pressures such as are normally present in city water mains, i. e., about 30 50 pounds per square inch, and with a supply of air under pressure such as may be readily provided by suitable air compressors. I attain this object by combining, in my nozzle, 35 a substantial quantity of atmospheric air with the air and water under super-atmospheric pressure. This materially increases the degree of atomization of the water and the rate of its flow or discharge from the 40 nozzle irrespective of its pressure.

Another object of my invention is to provide a discharge nozzle of the type referred 45 to which can also be used for drying the surfaces washed, which can be used for creating a partial vacuum such as may be adapted 50 for cleaning purposes, and which may be used for mixing with the water stream a quantity of other fluid such, for instance, as oil, for spraying a washed surface, or chemi- 55 cal for cleaning or other purposes, without

previously mixing the same with the water supply. This latter feature is highly desirable when my device is used for washing locomotives, railroad equipment and other objects in which it is required that oil be applied to the washed surfaces during or after the process of washing.

In the accompanying drawings which illustrate a selected embodiment of my invention—

Figure 1 is a vertical longitudinal section through my nozzle.

Figure 2 is a vertical transverse section taken on the line 2—2 of Figure 1.

Figure 3 is a front end elevation of my 65 nozzle.

Figure 4 is a side elevation of a detail of the valve structure used in my nozzle.

Figure 5 is a bottom view of a detail of my nozzle used in drying or vacuum cleaning 70 operations.

Figure 6 is a vertical transverse section taken on the line 6—6 of Figure 1.

Figure 7 is a detail section of a front end 75 of the discharge nozzle.

My device includes a receptacle 1 for air under pressures above atmospheric pressures, a passage 2 for air under atmospheric pressure (or for other fluids, as will be pointed out hereafter), a chamber 3 for the reception 80 of water, and a discharge portion 4 which is connected to another nozzle section 5 which should be of the desired length and shape best adapted for the work at hand. A preferred form of discharge nozzle is illustrated in my Patent No. 1,751,719, issued 85 March 25, 1930.

Admission of air to receptacle 1 and of water to chamber 3 is controlled by valve structures, one of which will be described in detail as comprising a cylindrical sleeve 6 having an annular seat 7 projecting into the somewhat larger housing 8. A cup-like member 9 is slidable in cylindrical sleeve 6 and carries a disk 10 on its outer end adapted 90 to contact with the annular seat 7 to seal the sleeve 6. The side wall of cup 9 is perforated adjacent to its bottom and the seat 10 and, when the cup is moved to the left of the position shown, it will admit fluid through 95 100

the perforations into the interior of sleeve 6. A suitable spring 11 yieldingly thrusts sleeve 9 to the right and disk 10 against its seat.

A valve crank member having journals 12 and 13, and an eccentrically disposed pin 14, is rotatably mounted in chamber 3 with its journal or stem 13 extending through the wall of the chamber and mounting a suitable operating handle 15.

- 10 I illustrate a packing gland in which a detachable section 16 of the chamber wall is provided with an opening in which the valve stem 13 is freely rotatable and slideable. The inner face of section 16 is provided with an annular ridge 16a surrounding the opening for the valve stem and the outwardly directed face of the disk 15a formed on the valve stem is provided with a corresponding annular ridge 15b. These ridges form opposing elements having restricted areas. A compressible element C, consisting of any suitable packing material, is placed between ridges 16a and 15b and a spring S yieldingly thrusts the valve stem outwardly of the chamber whereby the opening for the valve stem is sealed tight at all times. When fluid under pressure is present in the chamber, the same will tightly press the disk 15a against the packing material irrespective of spring S.
- 20 Due to the restricted engagement of the compressible material and the fact that the same is not forced against the stem, friction is reduced to a minimum and the valve handle may be freely rotated under all conditions.
- 25 When it is desirable to repack the gland, section 16 may be removed and another washer-like element C substituted for the used one.
- 30 A connecting link 17 is pivoted on the cross pin 18 on member 9 and engages the pin 14 on the crank member. Rotation of handle 15 in an anti-clockwise direction from the position shown in Figure 1 will move link 17, cup 9, and disk 10 to the left, opening the valve and permitting the access of water to chamber 3. The valve will be opened to the greatest extent when pin 14 is in its extreme left hand position where it will be in the same horizontal plane as journals 12 and 13, and hence will remain open until the 35 valve handle is rotated. A pin 19, mounted on the crank, is adapted to engage the edge of link 17 to limit the rotation of the crank in either direction.
- 40

Air admitted to receptacle 1 passes therefrom through the nozzle 20. A passage 2 for atmospheric air surrounds nozzle 20 and terminates in a nozzle 21 projecting forwardly from nozzle 20 and preferably terminating in a flaring section 22 of slightly larger diameter than the nozzle 20 which section, in turn, is surrounded by chamber 3 terminating in the nozzle 4 which is of slightly larger diameter than nozzle 22. Atmospheric air may be admitted to passage 2 through a valve 45 comprising member 23 and a rotatable sleeve

24, each having perforations 32 which may be aligned or disaligned to open or close the valve, respectively. Member 23 is also provided with a connection 25 to a tube 26 which may lead from a supply of oil, soap, polish, or other material which it may be desired to discharge with the washing stream or intermittently independently of the washing stream. A needle valve 27 adjusts or cuts off the supply of fluid through tube 26. A check valve 40 closes the entrance to chamber 2 whenever any back pressure in the latter exceeds atmospheric pressure.

50 Chamber 3 is provided with a downwardly disposed opening 28 which is fitted with a valve cage 29 having a valve disk 30 slidably mounted therein and adapted to seat at 31. When the valve 9, opening into chamber 3, is closed and air is passed through receptacle 1 and nozzles 20, 22 and 4, a partial vacuum will be created in chamber 3, in accordance with well-known pneumatic phenomena, and disk 30 will be raised from its seat, as indicated in Figure 1, admitting a large volume of atmospheric air into chamber 3 and increasing greatly the volume of air discharged by the tool. This great volume of air is used for blowing and drying purposes.

55 When valve 9 is opened and water under substantial pressure is admitted to chamber 3, the valve disk 30 will be returned to its seat and this opening in the chamber closed. By removing valve cage 29 and substituting a connection and tube, the vacuum created in chamber 3 may be used for vacuum cleaning.

60 The admission of air under pressure to receptacle 1 and its passage through nozzles 20, 22, and 4, will likewise draw atmospheric air in through perforations 32 and the free supply of atmospheric air to the air stream passing from nozzle 20 through nozzle 22 before the air stream is mixed with the water provides a greater volume of air and increases the atomization and velocity with 65 which water and air is discharged from nozzle 4. Similarly, when valve 9 is closed, and the device is used to create a vacuum through opening 28, the admission of atmospheric air through passage 2 substantially increases the degree of vacuum which may be created in chamber 3. For example, with passage 2 closed to the atmosphere, and air under pressure of eighty-five pounds per square inch admitted to receptacle 1, I can produce a 70 vacuum of eight inches of mercury in chamber 3 (it will be understood that valve 9 is closed). With passage 2 open to the atmosphere and other conditions the same, I can produce a vacuum of fourteen inches in chamber 3.

75 I utilize the upstanding portion of the device forming the wall of passage 2 for mounting the handle 33 which is affixed to the vertical web 34 by a bolt 35. The member 80

on which this handle is mounted is so located intermediate the ends of the horizontally disposed body of the device that the weight of the tool (when supply hose is connected 5 to the compressed air and water inlets) will be centered substantially beneath the handle 33 whereby the tool will be most easily carried and directed.

In order to protect the end of the discharge nozzle 5 from being injured by forcible contact with machines, the floor, or other hard objects, I surround the outer end of the same with a heavy washer-like-buffer 36 which is retained in place by suitable metal 15 washers 37 and a nut 38 screwed on the end of the nozzle so as to thrust the washers toward a collar 39 on the nozzle. This feature also serves to protect finished surfaces, on objects being washed, from being injured 25 by blows from the end of the discharge nozzle.

Obviously, the details of my invention may be modified without departing from the spirit thereof and I contemplate the exclusive 25 use of such variations as come within the scope of my claims.

I claim:

1. In a tool of the class described, a receptacle having a port for air under pressure, a discharge nozzle leading therefrom, a passage surrounding said nozzle having a port open to atmospheric air and an inlet for another fluid, a discharge nozzle leading from said passage and axially alined with 20 and slightly spaced from said first mentioned nozzle, a chamber having an inlet for water and a port open to atmospheric air, said water inlet having a manual valve therein and said third mentioned air port having a check valve 25 therein adapted to be actuated either by atmospheric pressure or the pressure within said chamber, according to which pressure is greater, and a discharge nozzle leading from 30 said chamber and alined with but slightly spaced from said second mentioned nozzle.

2. In a tool of the class described, a receptacle for air under pressure, a nozzle leading therefrom, a passage having separately operable elements for alternately admitting 50 atmospheric air and another fluid, a nozzle leading from said passage and surrounding said first mentioned nozzle and receiving the discharge from the latter, a chamber having an inlet for water and a port open to atmospheric air, and a nozzle leading from said chamber and surrounding said second mentioned nozzle.

3. In a tool of the class described, a receptacle for air under pressure, a nozzle leading 60 therefrom, a passage having separately operable elements for alternately admitting atmospheric air and another fluid, a nozzle leading from said passage and surrounding said first mentioned nozzle and receiving the discharge from the latter, a chamber having

an inlet for water and an inlet open to atmospheric air, a manual valve in said water inlet and an automatic check valve in said air inlet arranged to automatically admit atmospheric air to said chamber when said manual valve is closed, and a nozzle leading from 70 said chamber and surrounding said second mentioned nozzle.

4. In a tool of the class described, a receptacle having an inlet for air under pressure, a discharge nozzle leading therefrom, a passage including a lower part surrounding said nozzle, an upright portion in communication with said lower part, and a horizontal portion spaced from said lower part, an inlet open to atmospheric air and an inlet for another fluid in said portion, manual valves in said inlets, a check valve between said vertical and horizontal portions arranged to open when the pressure in said horizontal portion exceeds the pressure in said vertical portion, and a discharge nozzle leading from 80 said passage and surrounding said first mentioned nozzle.

5. In a tool of the class described, a receptacle having an inlet for air under pressure, a discharge nozzle leading therefrom, a passage including a lower part surrounding said nozzle and an upper part, a port open to the atmosphere and a fluid connection in said upper part, manual valves in said port and said connection, a check valve between said upper and lower parts and arranged to close communication therebetween when the pressure in said lower part exceeds the pressure in 90 said upper part, a discharge nozzle leading from said lower part and axially alined with said first mentioned nozzle, a chamber having an inlet for water and an inlet open to the atmosphere, a manual valve in said water inlet, a check valve in said air inlet arranged to open when atmospheric pressure exceeds the 95 pressure within said chamber, and a discharge nozzle leading from said chamber and alined with said second mentioned nozzle.

In testimony whereof I hereunto affix my signature this 30 day of April, 1928.
